LUBRICATING PUMP

Thomas R. Thomas, New York, N. Y., assignor to Auto Research Corporation, a corporation of Delaware

Application May 5, 1951, Serial No. 224,809

5 Claims. (Cl. 184—27)

The present invention relates to a centralized lubricating installation and it particularly relates to a centralized lubricating pump installation of light weight and compact construction adapted to be fitted upon and used in connection with portable tools and machines.

Although not limited thereto, the present invention will be particularly described in its application to a central lubricating pump for a portable textile sewing machine of the type utilized for cutting cloth in layers to be used in making garments, it is to be understood that it has a much broader and wider application to machinery in general.

Among the objects of the present invention is to provide a compact, light weight, readily installed, inconspicuous lubricating pump for portable machinery which may be readily mounted upon such machinery and associated therewith without substantially increasing the weight or bulk thereof and which will give assurance that the moving parts of such machinery will be adequately supplied with properly yet relatively minute quantities of lubricant during operation thereof.

Another object is to provide a novel, lubricating pump for textile sewing machinery which will not interfere with the operation, assembly, repair or maintenance of such textile sewing machinery, and which at the same time will give full and adequate assurance of full and complete lubrication thereof.

In the drawings wherein like reference characters denote corresponding parts throughout the several views:

Fig. 1 is a vertical view, partly in section, showing the central lubricating pump mounted on a sewing machine. 45

Fig. 2 is a transverse vertical sectional view of the pump construction.

Fig. 3 is a vertical transverse sectional view upon the line 3—3 of Fig. 2.

Fig. 4 is a horizontal transverse sectional view upon the line 4—4 of Fig. 2.

Fig. 5 is a fragmentary transverse sectional view upon the line 5—5 of Fig. 2.

Fig. 6 is a transverse vertical sectional view upon the line 6—6 of Fig. 2.

Fig. 7 is a side elevational view similar to Fig. 2, upon a reduced scale, showing an alternative construction with a double cam instead of the single cam of Fig. 2 and with a slightly longer drive shaft.

Fig. 8 is a side sectional view of an alternative construction which may be utilized to prevent any breakage or jamming in case of reverse rotation of the external drive shaft, upon the line 8—8 of Fig. 9.

Fig. 9 is a side elevational view taken from the line 9—9 of Fig. 8.

Fig. 10 is a front elevational view similar to Fig. 9 of the same device as applied to a double-lobe cam.

Fig. 11 is a vertical sectional view upon the line 11—11 of Fig. 12, showing the latch plate.

Fig. 12 is a front elevational view taken from the line 12—12 of Fig. 11.

Referring to Fig. 1, there is shown a sewing machine

2

which may be of the lock-stitch type, having a table A, a rear vertical support B, and an arm C.

The arm C is hollow, as indicated at 10, and it carries a central drive shaft 11.

5 The shaft 11 carries the eccentric head (not shown) which works the needle bars.

On the table A is mounted the pump D, which is driven by the belt 25, the pulley 26 and the lower pulley 27.

10 The lower pulley 27 in the lower part of the belt 25 is enclosed in a guard casing 28.

As shown best in Fig. 1, this belt extends obliquely and downwardly away from the neck or tubular member C.

15 As shown in Fig. 1, the arm or tubular member C is provided with openings at 29 and 30 at the top of the casing 28 to permit free passage of the belt 25.

The table A has a depending base 45.

The pump structure is best shown in Figs. 2, 3 and 4.

20 The pump structure D has a base 75 and a cover 76. The base has a bottom 77, the end walls 78 and 79 and the side walls 80.

The corners are provided with enlargements 81 having the mounting bolt holes 82.

25 The wall 78 has an enlargement 83 in which is press-fitted the window assembly E. The window assembly has a channel member 84 depressed to form the backing cup 86 with the flow openings 87 at the top and 88 at the bottom. This cup receives the transparent disc 85, which serves as a window.

30 The gasket 89 assures an oil-tight seal between the backing cup 86 and the transparent window 85. The press-fit of the channel 84 within the opening 90 assures an oil-tight connection at this point.

The cover 76 has the top wall 92, side walls 93 and 94 and the end walls 95 and 96.

35 The cover has an elongated recess 97 receiving the bearing sleeve 98 which terminates in the enlarged chamber 99 having the closing annulus 100. The bearing sleeve 98 receives the shaft 101, having the groove 102 with the extension 103. The extension 103 has the flat 104. The flat 104 on the extension 103 enables ready connection to an automatic drive.

The shaft 101 has a lubricating groove 105 within the sleeve 98 and it extends to the right, as indicated at 106, and carries the screw-thread 107 forming a worm which drives the gear 108.

The end of the shaft 101 has an enlarged portion or cap 109 which has the thrust bearing in the end 110 of the screw plug 111. The screw plug is threaded into a tapped opening 112 in the wall 96 of the cover 76.

40 The fillister head 113 fits in the recess 114. The worm 107 drives a gear train, as best shown in Fig. 9. The first unit of the gear train has a large gear 108 and the small pinion 115 which rides upon the shaft 116. The pinion 115 drives the next unit consisting of the gear 117 and the pinion 118 on the shaft 119.

45 The unit 117—118 through the pinion 118 drives the unit consisting of the gear 120 and the pinion 121 on the shaft 116.

The unit 120—121 in turn drives the gear 122 and the pinion 123 upon the shaft 119.

50 The unit 122—123 drives the unit consisting of the gear 124 and the pinion 125 on the shaft 116.

The unit 124—125 drives the unit consisting of the gear wheel 126 and the pinion 127 on the shaft 119.

55 The pinion 127 drives the gear wheel 128 which in turn drives the cam 129.

The cam 129 has the lobe 130 and the step 131 which cooperate with the follower projection 132 on the lever 133. The lever 133 is mounted upon the hub member 134 turning on the shaft 135.

60 The shafts 116 and 119 have spacer sleeves 150, 151

and 152 in respect to the depending hangers 153 and 154 depending from the cover 76.

At the ends of the shafts 116 and 119 are positioned the collars 155 and 156 to keep said shafts in position.

The shaft 135 has a support 157 in the structure 158 attached to the end wall 96. The other end of the shaft 135 is press-fitted into the recess 159 in the plug 160, which is screwed into the tapped opening 161.

The lever 133 has the rounded end portions 175 which fit in the groove 176 on extension 177 of the piston 178.

The piston 178 rides in the cylinder 179. The cylinder 179 has a lower tapped opening 180 which is closed by the threaded insert 181 carrying an inlet check valve.

The lower portion of the cylinder 182 has a metal cup 183 which receives the filter 184. The filter 184 has the two backing metal screens 185.

The pump may also be actuated by the hand actuator G.

The hand actuator G consists of a manual pull-up button 195 with the upper piston extension 196. The shaft 196 is encircled by the coil spring 197 which reacts upon the shoulder 198 and also on the thimble 199.

The thimble is supported against the base 200 of the cap 201. The cap 201 is interiorly tapped at 202, to be screwed upon the threaded nipple 203.

The pump cylinder 179, in Figs. 2, 3, 4 and 6, discharges through the outlet check valve 204, which feeds lubricant under pressure through a tube 205 and a coupling connection 606 (see Figs. 2 and 3). Lubricant passes through the vertical bore 608 to the tapped outlet connection 609 (see Fig. 3). Then the lubricant will flow out through the outlet 206, as shown in Fig. 1, to the external pipe 207.

The cover 76², in Fig. 1, has a screw filler cap 210, whereas in Figs. 2 and 3 it has the Gits type pivoted snap filler cap 412.

In the operation of the pump the drive may be directly from the machine at 103 and this drive is through the worm 107, the gear train H to the cam 129.

The cam 129 will partly lift the lever 133 and the piston 178. The piston 178 will be returned by the spring 197 when the follower 132 passes over the lobe 130 and down the step 131. To give an intermittent manual operation, the hand button 195 may be employed and this will draw up the piston 178 against the spring 197 whenever it is desired to give an additional "shot" of lubricant.

The Gits type filler cup 410 (see Figs. 2 and 5) fits in the recess 411 in the top wall 92 of the cover 76. The cup 410 has a cover 412 having a hinge 413 which is pressed into closed position by the coil spring 414. The lubricant that is poured into the reservoir D will pass through the conical passage 415 and the opening 416.

Referring to Fig. 6, the lubricating groove 105 on the shaft 101 inside the bearing sleeve 98 connects the passageway 217. This passageway 217 has a gasket connection 218 to the passageway 219 which opens into the recess 176 of the piston 178. Oil leakage of piston 178 thus provides lubrication for bearing sleeve 98. The gasket 218 in Fig. 6 will take up the clearance between the cover 76 and the pump body 179.

As shown upon Fig. 1, the lubricant fed from the pump D under pressure will first pass down through the tube 207 into the junction 208.

The junction 208 is held by the screws (not shown) upon the table structure A.

From the junction the lubricant will flow outwardly through the metering fittings (not shown) to bearings of the machine.

This relatively small lubricating pump will feed all of the important bearings of the sewing machine structure. The feed will be increased with the speed of the drive shaft 11, which drives the shaft 101 of the pump through the pulley 27.

Referring to the device of Figs. 8 and 9, the cam 510

will be mounted to turn upon the bearing sleeve 511. The bearing sleeve 511 has an enlargement 512 fitting in the shoulder 513. The sleeve 511 bears against the latch plate 514. The gear plate 128 is peened at 515 to the end of the sleeve 511.

The pin 516 is mounted and slides closely in the bore 517 in the cam 510. The bore 517 is enlarged, as indicated at 518, to receive the coil spring 519.

The pin 516 has a shoulder 520 with an end projection 521.

The end projection 521 bears upon the tongue 522, which is pressed out of the metal of the plate 514, as best shown in Figs. 19 and 20.

By referring to Figs. 11 and 12, it will be noted that the head or follower 521 of the pin 516 can move freely in the direction 523 toward the base of the tongue 522 when it is driven in reverse movement by the shaft 104 of the pump of Fig. 4 and the shaft 104' of the pump of Fig. 7, or by the drive belt 25 of the pump of Fig. 6.

Thus, there will be no danger of the cam 129 jamming against the follower element 132 of the lever 133 with resultant breakage.

On the other hand, when there is a direct drive in the direction 525 toward the end of the tongue 522, the head 521 will catch in the recess 524 and will drive the cam 129.

In Fig. 10 is shown a double cam 129⁴ with the two step members 131⁴.

The latching tongue 522⁴ will be placed in back of one lobe of the cam 129⁴ and will function in the same manner as has already been described in connection with Figs. 8, 9, 11 and 12.

The sewing machine may be of the Willcox & Gibbs type, but it is to be understood that other types of sewing machines may be similarly lubricated. Normally, with the Willcox & Gibbs type of sewing machine a reservoir with a rear side lubricant feed, as shown in Fig. 1, is preferred.

However, with other mechanism a top lubricant connection, as shown in Figs. 2 and 3, may be preferred.

The lubricating system, as shown, will oil all of the high speed bearings and will supply a correct oil film to each individual bearing automatically. The operator need not have any of her attention distracted by the lubrication of her machine and the operator may give all of her attention to the sewing operation with the assurance that lubrication will automatically result.

Normally, for every 60,000 revolutions of the main shaft a lubricant shot of about twelve drops of filtered oil will be fed to the bearings.

While there has been herein described a preferred form of the invention, it should be understood that the same may be altered in details and in relative arrangement of parts within the scope of the appended claims.

Having now particularly described and ascertained the nature of the invention, and in what manner the same is to be performed, what is claimed is:

1. A central reciprocating plunger lubricant pump for a centralized branched lubricating installation having an upright cup-shaped lubricant reservoir casing devoid of mechanism, an inverted cup-shaped cover for said casing, a drive shaft for said pump mounted in the sides of said cover cup and extending horizontally through and below the top of said cover and a cylinder extending through and depending downwardly from said cover and at its lower end being at the bottom of the lubricant reservoir casing so that it will be immersed in the lubricant body, a spring returned reciprocating piston in the lower end of said cylinder, said pump being characterized by a cam-lever piston actuator mechanism having a reduction gear drive train with parallel vertically superimposed horizontal shafts, the axes of which are positioned in the same vertical plane, said train being driven by said drive shaft and in turn driving said piston, said train having intermeshing gear wheel and pinion reduction

units alternately carried on said superimposed shafts and the ends of said shafts being carried by the sides of said cup.

2. The pump of claim 1, in which the sides of the cup which carry said shafts telescope into the upright lubricant casing.

3. The pump of claim 1, the upper end of said cylinder being threaded and said threaded end portion projecting through an opening in the top of said cup cover and a cap nut clamping said cylinder in position.

4. The pump of claim 1, the last gear in said gear train being provided with a cam tongue member and said cam having a spring pressed plunger riding against said depressed tongue so that said gear will drive said cam in one direction but not in a reverse direction.

5. The pump of claim 1, in which the last gear has a hub upon which the cam is positioned and in which said last gear and cam have a lost motion connection consisting of a depressed tongue stamped out of the periphery of the gear and a spring pressed follower stud carried by 20 said cam.
